UNITED STATES PATENT OFFICE.

FRED H. CORTHELL, OF ELGIN, ILLINOIS, ASSIGNOR OF ONE-HALF TO
GEORGE E. HUNTER, OF SAME PLACE.

DEVICE FOR SUSPENDING LAMPS.

SPECIFICATION forming part of Letters Patent No. 416,255, dated December 3, 1889.

Application filed August 31, 1889. Serial No. 322,548. (No model.)

To all whom it may concern:

Be it known that I, FRED H. CORTHELL, a resident of Elgin, in the county of Kane and State of Illinois, have invented certain new and useful Improvements in Devices for Suspending Lamps; and I do hereby declare the following to be a full, clear, and exact description of the invention, such as will enable others skilled in the art to which it pertains to make and use the same.

The object of the invention is to effect, through the balancing power of a spring, the vertical adjustment of electric lamps which are suspended by means of flexible conductors; and it consists in the construction hereinafter described, and pointed out in the claims.

In the accompanying drawings, Figure 1 is a vertical central section of the novel device, taken lengthwise of the drum. Fig. 2 is a similar section on line $x-x$ of Fig. 1. Fig. 3 is a plan of the device with the top removed. Figs. 4 and 5 are respectively an elevation and plan of the drum and its frame, showing the position of the ratchet and retaining-pawl with reference thereto. Figs. 6, 7, 8, 9, and 10 are views of details and modifications.

Like letters refer to like parts in all the above figures.

30 The construction includes an ornamental case of sheet metal in three parts—viz., the body a , the top a' , and bottom a'' —having notches to allow the passage of the lugs n n' n'' n''' , whereby they are secured to the body.

35 B is a frame secured by soldering or otherwise within the body a , as indicated at B, having the openings b and b' to receive the journals of the drum-shaft C.

D is a drum, preferably of wood, having the 40 transverse opening J for a suspending-cord, and c a spiral spring inclosed in the metallic spring-box d and attached thereto and to the drum by means of the spring-hook r.

C indicates a drum-shaft having the ratchet 45 f firmly fixed thereto, and g a winding-lever loosely fitted thereon and movable between the said ratchet f and the frame and carrying the winding-pawl h.

x is a retaining-pawl that holds the ratchet- 50 drum shaft and spring while the winding-pawl is moving forward to engage an ad-

vanced tooth. It can be tripped by lever x' .

i denotes a hook engaging its spring at its inner end or at the center of the coil and connecting it to the shaft. The screws k 55 and k' engage the drum-shaft or stationary axis C, forming extensions thereof, and facilitate the putting together of the parts.

The following is a description of the method of putting the device in operation, reference 60 being had to Figs. 1, 2, 3, 4, and 5: The lamp being disconnected, its suspending-cord is passed through the opening y in the case, and thence through the opening j in the drum D, and thence out of the case through the opening y' . The lamp is now connected to the cord and the adjusting device placed in the desired position on the same and the lower portion of the case a'' disconnected from the body a . This is effected by turning the part 70 a'' until the lugs n and n' will pass its notches. The bottom a'' can then be slipped down on the cord far enough to allow the winding-lever g to be operated to move the notched drum-shaft by means of the pawl h, whereby 75 is put upon the spring c the tension required to balance the lamp within the limits desired. After the spring is wound, as above stated, the bottom of the case is replaced upon the body and the device is ready for use. It will 80 of course be understood that the turning by means of the lever g and pawl h of the ratchet fixed to the drum-shaft increases the tension of the spring or winds it up, one end of the spring being fixed by pin or hook r to the 85 drum, which is held from rotation by the cord that passes through opening j, except so far as the cord is wound upon the drum, and the other end to the shaft C by the hook or pin i. The spring, when thus wound up, counter- 90 balances or aids in counterbalancing the lamp by its effect upon the suspending-cord through the medium of the drum. The passage of the suspending-cord through the drum provides that it may be situated in or 95 near the axis of the case.

The case may be made of any desirable contour and variously ornamented, and may be made in two parts instead of three, and the parts may be connected by other devices 100 than those described. The part a may in some cases be omitted, or parts a and a' might

be made integral with each other, and other portions of the device may be varied by mechanical skill without departing from the invention.

5 In Figs. 6 and 7 is shown a supplementary device, which can be used, if desired, consisting of the centrifugal pawls $v v'$, pivoted at t to the drum and adapted to engage the ratchet o , fixed to frame B. These pawls are 10 similar in mechanical operation to well-known curtain-fixtures, and serve to hold the drum and lamp when the latter has been placed in the required position, and are especially applicable in case that it is desired 15 that the spring shall constantly more than balance the lamp.

The operation of the spring c may, if desired, be aided by a second spring p , as indicated in Figs. 9 and 10. q is a box inclosing 20 the same, and s a tubular extension or shaft fixed to said box q , and to this tubular shaft s spring c is connected by the pin or hook i . The spring p is also connected at one end to box q and at the other to the shaft C. The 25 turning of the shaft to increase the tension of the spring c will, through the medium of the latter, turn the sleeve or shaft s and box q , and thus increase the tension of the spring p also, and in operation the latter spring will 30 aid the former, and thus increase or widen the limits of an approximately uniform tension of the springs.

The case herein described, which may be made of any suitable material, is not essential 35 to the operation, nor is the particular frame. If the case were wholly omitted, the device could yet be used to apply the tension of the spring to a suspending cord, chain, wire, or equivalent, and the spring will tend to turn 40 the drum about the shaft, and will therefore tend to lift the cord independently of the case or the special form of the frame. Should the drum not be held during the operation of winding the spring, it is evident that at least 45 a portion of the cord would itself become wound upon the drum, and thus it is apparent that tension may be put upon the spring by winding a surplus of cord upon the drum, and then unwinding that surplus by pulling 50 upon the cord, the drum-shaft being held from rotation. Likewise various mechanisms operating to turn the drum-shaft could be substituted by mechanics without sacrificing the advantage of the improvement.

55 Having thus described my invention, what I desire to secure by Letters Patent is—

1. In a suspending device, the combination

of the suspending-cord, the drum mounted loosely on a shaft and provided with a transverse opening to receive said cord and adjustable thereon, and a spring having one end attached to the drum and the other to the shaft, and mechanism for turning the shaft to give tension to the spring, substantially as set forth. 60

2. In a suspending device, the combination of the suspending-cord mounted loosely on a shaft, and the drum provided with a transverse opening to receive said cord and adjustable thereon, and a spring having one end attached to the drum and the other to the shaft, and mechanism for turning the shaft to give tension to the spring, and an inclosing-case, also adjustable on the cord, substantially 70 as set forth. 75

3. In a suspending device, the combination of the suspending-cord mounted loosely on a shaft, the drum provided with a transverse opening to receive said cord and adjustable thereon, and a spring having one end attached to the drum and the other to the shaft, and mechanism for turning the shaft to give tension to the spring, and an inclosing-case, also adjustable on the cord and having a part or section made detachable to give access to the mechanism, substantially as set forth. 80 85

4. In a suspending device, the combination of the suspending-cord mounted loosely on a shaft, and the drum provided with a transverse opening to receive said cord and adjustable thereon, and a spring having one end attached to the drum and the other to the shaft, and mechanism for turning the shaft to give tension to the spring, and the supplementary spring, substantially as set forth. 90 95

5. In a suspending device, the combination of the suspending-cord mounted loosely on a shaft, and the drum provided with a transverse opening to receive said cord and adjustable thereon, and a spring having one end attached to the drum and the other to the shaft, and mechanism for turning the shaft to give tension to the spring, and the centrifugal pawls pivoted on the drum, and the ratchet connected to the shaft, substantially as set forth. 100 105

In testimony whereof I have signed this specification in the presence of two subscribing witnesses.

FRED H. CORTIHELL.

CHAS. P. CORLIS.

Corrections in Letters Patent No. 416,255.

It is hereby certified that in Letters Patent No. 416,255, granted December 3, 1889, upon the application of Fred. H. Corthell, of Elgin, Illinois, for an improvement in "Devices for Suspending Lamps," errors appear in the printed specification requiring correction, as follows: In lines 68, 78, 90, and 99 the words "the drum" should be stricken out, and inserted after the words "suspending-cord" in lines 67, 77, 89, and 98, respectively; and the said Letters Patent should be read with these corrections therein that the same may conform to the record of the case in the Patent Office.

Signed, countersigned and sealed this 24th day of December, A. D. 1889.

[SEAL.]

CYRUS BUSSEY,

Assistant Secretary of the Interior.

Countersigned:

C. E. MITCHELL,

Commissioner of Patents.
